Primary Examiner—Stella M Reid*Assistant Examiner*—Shanda C Hill(74) *Attorney, Agent, or Firm*—Leason Ellis LLP(57) **CLAIM**

The ornamental design for shirts arranged in a box, as shown and described.

DESCRIPTION

FIG. 1 is a top and side perspective view of shirts arranged in a box showing my new design;

FIG. 2 is a top plan view thereon, the bottom being a mirror image thereof;

FIG. 3 is a left side elevation view thereof, the right side being a mirror image thereof;

FIG. 4 is a first end elevation view thereof; and,

FIG. 5 is a second end elevation view thereof.

The broken lines of FIGS. 1–5 are for illustrative purposes only to show exemplary buttons and a shirt placket and form no part of the claimed design.
